UNITED STATES PATENT OFFICE

133,923

DESIGN FOR A RING

Saul Rubin, Chicago, Ill.

Application April 2, 1942, Serial No. 106,431

Term of patent 3½ years

To all whom it may concern:

Be it known that I, Saul Rubin, a citizen of the United States, residing at Chicago, county of Cook, and State of Illinois, have invented a new, original, and ornamental Design for a Ring, of which the following is a specification, reference being had to the accompanying drawing, forming a part thereof, in which:

The figure is a perspective view of a ring embodying my new design.

I claim:

The ornamental design for a ring, as shown.

SAUL RUBIN.
